UNITED STATES PATENT OFFICE

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

1,283,727.

Specification of Letters Patent. Patented Nov. 5, 1918.

Application filed September 24, 1917. Serial No. 192,864.

To all whom it may concern:

Be it known that I, JEROME R. GEORGE, a citizen of the United States, residing at Worcester, in the county of Worcester and 5 Commonwealth of Massachusetts, have invented certain new and useful Improvements in Rolling-Mills, of which the following, taken in connection with the accompanying drawings, is a specification, the present 10 application being a continuation in part of my previous application, Serial No. 868,912, filed October 27, 1914.

Among the objects of my invention is to increase the capacity of rolling mills, particularly merchant mills, and to enable the 15 product of such a mill to be varied in size and dimension, the treatment of said product being continuous, as in the usual form of mill, from the heating furnace to the cooling bed on which the product is finally received.

The above and other objects are accomplished by the novel disposition and arrangement of the various stands and trains of rolls in a rolling mill, as hereinafter described, reference being had to the accompanying drawings in which

Figure 1 is a diagrammatic plan view of an arrangement of apparatus which is suitable for the carrying out of my invention.

30 Fig. 2 is a similar view of the same apparatus in a slightly modified arrangement.

Like reference characters refer to like parts in the different figures.

Referring particularly to Fig. 1, I have 35 indicated at 1 a portion of a heating furnace, from which the metal is delivered, for continuous reduction, to a train of rolls 2, by any suitable delivery means. The train of rolls 2, hereinafter referred to as a roughing train, may consist of any number of stands of rolls for the continuous and progressive initial reduction of the metal emerging from the furnace 1, said train being herein illustrated as consisting of four stands 40 of rolls which are driven by suitable gearing from an independent prime mover, such as a motor 3. In the line of delivery of the metal from the roughing train 2 is preferably disposed one or more stands of feed rolls 4, 4, here shown as two in number, and driven through suitable gearing from an independent prime mover, such as a motor 5. The stands of rolls serve for the delivery of 45 the heated product, as reduced in section by 50 the roughing train 2, to a suitable guide 6

which is arranged in the line of delivery of the metal from the roughing train 2 and feed rolls 4, 4.

In common with other mills the present invention contemplates, among other things, 60 the treatment of the heated metal in a train of rolls constituting a finishing train therefore, previous to the delivery of said metal onto a cooling bed. However, the present invention contemplates a novel disposition 65 and arrangement of the stands of rolls which constitute such a finishing train, by the location of said rolls at one side or the other, or both, of the line of delivery of the metal through the guide 6. As shown in 70 Fig. 1, such a finishing train may consist of one or more stands of rolls 7 and 8, and in the present instance, for convenience of illustration, only one each of such stands is shown. The rolls of the stand or stands 7 75 are capable of rotation by suitable gearing from an independent prime mover, such as a motor 9, to move the metal in a direction opposite to its passage through the guide 6, which latter may have a suitable curved 80 branch or guide 10 for delivering the metal to the rolls of stand or stands 7. The stand or stands 8 which form part of this finishing train are adapted to receive the metal in a loop 11 from the stand or stands 7, and 85 are driven by suitable gearing from an independent prime mover, such as a motor 12. The above finishing train elements are duplicated on the opposite side of the line of 90 delivery of the metal in guide 6, by the initial stand or stands 13, driven by an independent motor 14, and receiving the metal through a curved branch or guide 15, and by a final stand or stands 16, receiving the metal by a loop 17 and driven from a suitable motor 18.

In the operation of the apparatus thus far described, a variety of modes of treatment for the heated metal may be availed of, by reason of the particular arrangement 100 and disposition of the stands constituting the final or finishing trains on opposite sides of the line of delivery of the metal. For instance, if desired, the guide 6 may be employed to conduct the metal directly to the 105 cooling bed, in its original line of delivery from the roughing train 2 and the stands of feed rolls 4, in which case said stands 4 will serve as the final or finishing rolls of the mill. As herein shown, the guide 6 termi- 110

nates in forked branches 19 and 20, through which the rolled metal may be conducted selectively, from said guide to either one of a pair of receiving troughs 21, 22, which are associated with opposite sections 23 and 24, respectively, of a cooling bed 25. Or, if desired, the metal passing through guide 6 may be deflected through the curved branch 19 and passed through the stands of rolls 7 and 8, and thence conducted to the cooling bed 25 by a guide 26. In the same way the metal in guide 6 may be deflected through curved branch 15 through the stands 13 and 16 and thence conducted to the cooling bed 25 by a guide 27. The delivery guides 26 and 27, on opposite sides of the central guide 6, are enabled to deliver the metal, selectively, to either receiving trough 21 or 22 of the cooling bed, since they are connected with said central guide 6 by cross guides 28 and 29, respectively.

It will thus be seen by the provision of stands of finishing rolls on opposite sides of the main line of delivery of the metal that a mill of great flexibility is afforded, since either the rolls of stands 4, 8, or 16 can be used indiscriminately as the final finishing rolls of the mill from which, if desired, the metal can be conducted to the same or another section of the cooling bed 25. The passes of stands 8 and 16 may vary in size or shape, enabling two distinct products to be alternately rolled in the same mill, and if desired, one product can be conducted to the receiving trough 21 and cooled on the section 23 of the cooling bed, and the other product can be conducted to the receiving trough 22 and cooled upon the section 24 of the cooling bed.

As a further possibility of operation, which may or may not be availed of, as desired, the rolled product from either of the final stands 8 or 16 may be deflected from the respective longitudinal guides 26 or 27 into cross guides 28 or 29, which merge into the center guide 6 near the curved branches 19 and 15. In this way the rolled product from the finishing stands on one side of the main line of delivery may be carried across to the finishing stands on the opposite side of the main line of delivery. The stands 7, 8, 13, and 16 thus operate in series upon the product, rather than in parallel as heretofore described.

As shown in Fig. 4, the initial finishing stands 7 and 13, which are adapted to advance the metal in the opposite direction to its passage through the center guide 6, are located at a considerable distance from said center guide. The stands 8 and 16, however, are located much nearer to the center guide than their associated stands 7 and 13, respectively. Preferably, also, as herein shown, the stands 8 and 16 are offset from each other with reference to

the line of delivery to the metal, so as to afford a longitudinal space between them for the passage of an attendant in managing the loops 11 and 17. It will be understood of course, that in the operation of the mill, in any of the various modes involving the stands 8 and 16, the rolls of stands 7 and 13 may be separated and thrown out of commission, or may be used simply as forwarding means to deliver the metal to their respective associated stands 8 and 16.

In the modified arrangement shown in Fig. 2, the same disposition of finishing stands with respect to the roughing train 2, feeding stands 4, 4, and delivery guide 6 is adopted, but advantage is taken of the independent motor drive of the final finishing stands 8 and 16 for rotating the rolls of said stands in the reverse directions. This enables the heated metal to be deflected from the delivery guide 6 directly into either of the stands 8 or 16 by means of curved repeaters 30 or 31, respectively, and thence from either one of said stands into the other by means of a curved guide 32. In other words, if it is desired to finish the rolled product through the passes of stands 8 and 16 only, without passing it through the stands 7 and 13, the rolls of one of said stands 8 or 16 are simply reversed in direction, to direct the metal back through the curved guide 32 into the other of said stands, whose rolls are allowed to rotate in the normal direction, for advancement of the product to the cooling bed. Such advancement takes place through either one of the guides 26 or 27, in precisely the same manner as described with reference to Fig. 1. The apparatus of Fig. 2, with the additions above noted, is precisely the same as the apparatus of Fig. 1, except that a greater spacing of the stands 8 and 16 from the delivery guide 6 is availed of, to give the requisite turning radius for the metal in the curved repeaters 30 and 31.

This arrangement, by virtue of the individual motor drives for each of the stands 7 and 13 affords additional modes of operation from those above specified in connection with the selective reversal of the stands 8 and 16. For instance, when the metal is led in the reverse direction through either of stands 8 or 16 by the repeaters 30 or 31 respectively, instead of being directed through curved guide 32, it may be deflected into curved guide 33 or 34, as the case may be, and thence through either of the stands 7 or 13, which for this purpose, are caused to rotate in the same direction as the stands 2 and 4. Branch guides 35 and 36 are provided to deliver the metal into either of the guides 26 or 27, and it will be understood that by using the cross guides 28 and 29, the two parallel trains above de-

scribed may be run together in series, with the metal passing successively either through stands 8, 7, 16 and 13 or 16, 13, 8 and 7.

It is to be understood that the two forms 5 of my invention as above shown and described are illustrative merely of the general principles underlying the same; said principles find embodiment in the disposition of finishing rolls on opposite sides of the line 10 of delivery of the roughing and feeding rolls of a mill, said finishing rolls on each side being at different distances from said line of delivery, and all adapted to run, selectively, in the same or the opposite direction 15 to the roughing and feeding rolls, and also to the ultimate direction of the metal in the train. Such an arrangement is susceptible of numerous immaterial variations 20 from the forms proposed herein, especially in the manner of conducting the metal toward and from the finishing rolls, wherein the greatest latitude may obviously be availed of, without departing from the spirit and scope of my invention, as expressed in the appended claims.

I claim,

1. In a rolling mill, the combination with feed rolls for supplying metal to the rolls of a finishing train, of a finishing train comprising 30 rolls running in the opposite direction to said feed rolls and spaced from the line of delivery from said feed rolls, and delivery rolls adapted to run in the same direction as said feed rolls and located nearer to their line of delivery than the first mentioned rolls of said finishing train.

2. In a rolling mill, the combination with feed rolls for supplying metal to a finishing train, of a finishing train comprising 40 rolls running in the opposite direction to said feed rolls and spaced from the line of delivery of said feed rolls, and delivery rolls adapted to run in the same direction as said feed rolls, said finishing rolls being in staggered relation to each other, with the delivery rolls nearer to the line of delivery of said feed rolls.

3. In a rolling mill, the combination with feed rolls for supplying metal to a finishing 50 train, of a finishing train comprising stands of rolls on each side of the line of delivery from said feed rolls but spaced therefrom, each of said stands running in opposite directions to said feed rolls, and stands of rolls on each side of the line of delivery of said feed rolls and nearer thereto than the first mentioned finishing stands.

4. In a rolling mill, the combination with feed rolls for supplying metal to a finishing 60 train, of a finishing train comprising stands of rolls on each side of the line of delivery from said feed rolls but spaced therefrom, each of said stands running in opposite directions to said feed rolls, and stands of 65 rolls on each side of the line of delivery

of said feed rolls and nearer thereto than the first mentioned finishing stands, the last mentioned finishing stands adapted to run in the same direction as said feed rolls, and being staggered with respect to said first 70 mentioned stands.

5. In a rolling mill, the combination with feed rolls for supplying metal to a finishing train, of a finishing train comprising stands of rolls on each side of the line of 75 delivery from said feed rolls but spaced therefrom, each of said stands running in opposite directions to said feed rolls, and stands of rolls on each side of the line of delivery of said feed rolls and nearer thereto than the first mentioned finishing stands, the last mentioned finishing stands being staggered with respect to each other.

6. In a rolling mill, the combination with feed rolls for supplying metal to a finishing 85 train, of a finishing train comprising stands of rolls on each side of the line of delivery from said feed rolls but spaced therefrom, each of said stands running in opposite directions to said feed rolls, and 90 stands of rolls on each side of the line of delivery from said feed rolls but nearer thereto, than said first mentioned stands, said last mentioned stands adapted to run in the same direction as said feed rolls, and 95 being in staggered relation to the corresponding first named stands and also in staggered relation to each other.

7. In a rolling mill, the combination with feed rolls for supplying metal to a finishing 100 train, and a guideway leading from said feed rolls, of a finishing train comprising stands of rolls on each side of said guideway and spaced therefrom, adapted to run in the opposite direction to said feed rolls, 105 additional stands of rolls on each side of said guideway and nearer thereto than said first mentioned stands, and adapted to run in the same direction as said feed rolls, a cooling bed, a pair of guideways leading 110 from each of said last mentioned stands of rolls to said cooling bed, and cross guideways connecting said pair of guideways and placed obliquely thereto.

8. In a rolling mill, the combination with 115 feed rolls for supplying metal to a finishing train, of receiving mechanism for the finished metal; a guideway leading from said feed rolls to said receiving mechanism, a finishing train comprising a stand of rolls 120 on each side of said guideway, spaced therefrom and running in the opposite direction to said feed rolls, curved guideways leading from said first named guideway to each of said stands of rolls, additional stands of 125 rolls on each side of said first named guideway, nearer thereto than said first mentioned stands and adapted to rotate in the same direction as said feed rolls, guideways leading from said last mentioned stands of rolls 130

to said receiving mechanism, and cross guideways connecting said last mentioned guideways and communicating with the guideway from said feed rolls.

5 9. In a rolling mill, the combination with a roughing train, of stands of rolls on opposite sides of the line of delivery from said roughing train, to reverse the direction of the metal from said train and stands of 10 rolls receiving the metal from said reversing stands to continue its forward movement, said last named stands being close to the line of delivery of said roughing train.

10. In a rolling mill, the combination with 15 a roughing train, of stands of rolls on opposite sides of the line of delivery from said roughing train, at different distances therefrom, the stands farthest removed being constructed to reverse the direction of 20 metal as received from said line of delivery and the nearer stands being constructed to receive the metal from said reversing stands, and operating to continue its forward movement in the direction of said line of delivery.

25 11. In a rolling mill, the combination with a roughing train of stands of rolls on opposite sides of the line of delivery from said roughing train, at different distances therefrom, the stands farthest removed being constructed to reverse the direction of 30 metal as received from said line of delivery and the nearer stands being provided with means to receive the metal from said reversing stands, and operative to continue its 35 forward movement in the direction of said line of delivery, and means for selectively conducting the metal from said roughing train to the associated stands on one side or the other of said line of delivery.

40 12. In a rolling mill, the combination with a roughing train, of stands of rolls on opposite sides of the line of delivery from said roughing train, at different distances therefrom, the stands farthest removed being constructed to reverse the direction of 45 metal as received from said line of delivery, and the nearer stands being constructed to receive the metal from said reversing stands and to continue its forward movement in the 50 direction of said line of delivery, means for selectively conducting the metal from said roughing train to the associated stands on one side or the other of said line of delivery, and means for selectively delivering the 55 metal from each set of associated stands to the other set on the other side of said line of delivery, or continuing its forward movement in the direction of said line of delivery.

13. In a rolling mill, the combination with 60 a roughing train, of stands of rolls on

opposite sides of the line of delivery from said roughing train, at different distances therefrom, means for operating the nearer stands in the opposite direction to said line of delivery, means for operating the further stands in the same direction as said line of delivery, and means for conducting the metal from the nearer to the further stands on each side of said line of delivery.

14. In a rolling mill, the combination with 65 a roughing train, of stands of rolls on opposite sides of the line of delivery from said roughing train, at different distances therefrom, means for operating the nearer stands in the opposite direction to said line of delivery, means for operating the further stands in the same direction as said line of delivery, means for conducting the metal from the nearer to the further stands on each side of said line of delivery and means 70 for conducting the metal from the further stand on one side to the nearer stand on the other side.

15. In a rolling mill, the combination with 75 a roughing train of stands of rolls on opposite sides of the line of delivery from said roughing train, at different distances therefrom, on each side, means for selectively operating the nearer and the further stands in the same or the opposite direction 80 to the rolls of the roughing train, with said nearer and further stands in the reverse directions to each other, and means for initially conducting the metal from said line of delivery to the oppositely rotating stands, 85 and thence to the other stands on the same side.

16. In a rolling mill, the combination with 90 a roughing train, of stands of rolls on 95 opposite sides of the line of delivery from said roughing train, at different distances therefrom, the stands farthest removed being constructed to reverse the direction of metal as received from said line of delivery and the nearer stands being constructed to 100 receive the metal from said reversing stands, to continue its forward movement in the direction of said line of delivery, said nearer stands also being provided with selectively operated means to receive the metal directly from the line of delivery and means 105 for conducting the metal from each of said nearer stands to the other.

Dated this fourteenth day of September, 1917.

JEROME R. GEORGE.
